DESIGN FOR AN ENSEMBLE DRESS

Emil Schwartz, New York, N. Y.

Application November 11, 1935, Serial No. 59,467

Term of patent 3½ years

To all whom it may concern:

Be it known that I, Emil Schwartz, a citizen of the United States of America, residing in Manhattan, county of New York, and State of New York, have invented a new, original, and ornamental Design for an Ensemble Dress, of which the following is a specification, reference being had to the accompanying drawing, forming part thereof, wherein,

The parallel lines extending around the sleeves of the jacket, and on the collar and front panel portion of the dress member of the ensemble, represent tucks edged with contrastingly colored fabric.

I claim:

The ornamental design for an ensemble dress, substantially as shown, and described.

EMIL SCHWARTZ.
